[57] CLAIM

The ornamental design for a marine instrument cover, as shown and described.

DESCRIPTION

FIG. 1 is a perspective view of a marine instrument cover showing my new design;

FIG. 2 is a top plan view thereof;

FIG. 3 is a front elevational view thereof;

FIG. 4 is a right side elevational view thereof, the left side elevational view being a mirror image;

FIG. 5 is a rear elevational view thereof;

FIG. 6 is a bottom plan view thereof; and,

FIG. 7 is a perspective view analogous to FIG. 1, but with the cover opened.
